HEAD FOR SPINNING, DRILLING, AND
THE LIKE

Arthur Nyquist, Grandville, Mich., assignor to
Winters & Crampton Corporation, Grandville,
Mich., a corporation of Michigan

Application September 19, 1949, Serial No. 116,527

7 Claims. (Cl. 74—22)

1

The present invention relates to a power driven head which is adapted for use in spinning, drilling, reaming, countersinking and other similar mechanical processes, and which is directed to a novel structure for the attainment of such spinning and the like rapidly and efficiently. It is a primary object and purpose of the present invention to provide a head with mechanism organized and assembled for rapid spinning, drilling and other like processing of metal by means of which such processes are effectively carried out, the structure being sturdy, durable and practical and equipped with means for adjustment which permits correcting and spinning, countersinking or other processing while the head is in operation, thereby obtaining correct results, substantially instantly as against trial and error methods which would be required if any correction of the position of the tools had to be done while the machine was at rest.

A further object of the invention is to provide a head having mechanism therewithin which performs a spinning, drilling or other operation in a predetermined period of time governed by one rotation of a shaft in the machine, which is automatically stopped at the completion of such shaft rotation, and is started through novel means by the operation when a spinning, drilling or other operation is to be performed. Other objects and purposes and mechanism for the efficient attainment of the same will appear and be understood from the following description, taken in connection with the accompanying drawings, in which,

Fig. 1 is a longitudinal section through the head of my invention substantially on the plane of line 1—1 of Fig. 3.

Fig. 2 is a similar section in a plane generally parallel to the plane of Fig. 1, parts being broken away for better disclosure.

Fig. 3 is a similar section at right angles to Figs. 1 and 2 substantially on the plane of line 3—3 of Fig. 2.

Fig. 4 is a fragmentary enlarged elevation illustrating a modification in the cam structure for controlling the feed of a drill, countersink or the like.

Fig. 5 is an end elevation.

Fig. 6 is a fragmentary section showing the bearing mounting at one end of the controlling cam carrying shaft.

Fig. 7 is a fragmentary enlarged section illustrating the connection between the driving spindle and the tool carrying spindle, permitting longitudinal movement of the tool carrying spindle for tool feeding and withdrawal, and

2

Fig. 8 is a horizontal section substantially on the plane of line 8—8 of Fig. 2.

Like reference characters refer to like parts in the different figures of the drawings.

5 The head includes a hollow housing 1 in which the major portion of the mechanism is contained and which housing is filled with oil. The housing has at one side flanges 1a for the securing of it to a suitable support. The head may 10 be located either horizontal or vertical. In a horizontal position it may be attached to a suitable bed by bolts or other fastening means connected with the flanges 1a, and in vertical position to a suitable vertical post or other support 15 by attachment of such flanges thereto. In the drawings the head is illustrated in vertical position but it is to be understood that it is equally usable in horizontal position.

At one end of the housing, the upper end as 20 shown in the drawings, the housing is closed by plate 2. A driving shaft 3 shown equipped with a driving pulley 4 extends downwardly through the top plate 2 into the housing and is connected by a coupling 5 with a shaft or spindle 6 in alignment therewith, the upper end portion of which extends through suitable anti-friction bearings 7 carried by an arm which is permanently secured to a plate 8 located against and connected to one of the sides of the housing 1 (Fig. 2.) The shaft 6 is equipped with a worm 9 below 25 which (Fig. 7) is a supporting arm 10 into which the lower end of the spindle 6 extends and rotates, being enlarged in diameter and interiorly bored upwardly from its lower end axially, making a hollow shaft section 11 as shown.

30 The upper end portion of a tool carrying shaft or spindle 12 is slidably received in the axial opening of the section 11. The shaft 12 at its upper end portion is provided with a plurality of grooves 13 around it, usually 4 in number.

35 Pins 14 carried on the sleeve section 11 of the shaft 6 are fastened at their inner ends to shoes 15 located in and slidably lengthwise of the grooves 13. This provides a spline connection 40 between the shafts 6 and 12 so that the shaft 12 may be directly rotated by the shaft 6 but have longitudinal movements with respect thereto.

45 Between the lower end of the worm 9 and the bracket or arm support 10 below it an anti-friction thrust bearing is provided. The shaft 12 between the arm or bracket support 10 and the lower end of the housing has a collar 16 thereon, integral with or permanently secured thereto, above which is a roller bearing 17 with upper and lower retainers, as shown, against the upper surface of which a plate 18 is positioned. The 50

lower side or bottom of the housing 1 has a relatively large opening therethrough in which the upper end of a member 19 is received. The member 19 has an axial opening through it for the passage of the lower and somewhat enlarged portion of the shaft 12. The member 19 is fixedly secured to the housing and extends below it. A compression spring 20, preferably of the form shown, is located between the member 19 and the collar 16 with a thrust bearing between the upper end of the spring and the lower side of the collar, the normal action of which is to move the shaft 12 to upper position.

A worm wheel 21 on a shaft 23, mounted at its ends in roller bearings (Fig. 3), meshes with and is driven by the worm 9. A gear 23 also on shaft 22 drives a larger gear 24 with which it is engaged which is loosely mounted upon a shaft 26 paralleling the shaft 22 and below it in the vertical position of the head. At the inner face of the gear 24 one member of a clutch 25 is formed integral with the gear. The shaft 26 (Fig. 6) has a narrow collar 26a abutting a bearing 26c which is retained in its indicated position by a circular plate 26b through which the shaft 26 passes. The gear 24 may rotate freely upon the shaft 26 but will drive such shaft when a co-operating clutch member 27 splined on the shaft connects with the clutch member 25. Such clutch member 27 normally will connect with the clutch member 25 through the pressure of a spring 28 around the shaft 26 which is located between clutch member 27 and a cam 29 fixed to the shaft 26.

A lever 30 has two sides connected together between which, substantially mid-way between its ends, a transverse roller 31 is mounted for rotation to bear against the cam 29. The free ends 30a of the sides of the lever 30 extend to and over the plate 18 and are rounded at their edges to bear against such plate. The opposite end of the lever 30 is pivotally mounted at 32 on an adjustable fixture 33 which is slidable at one end portion in a guide 34 on a side of the housing 1, and at the other end has connection with an adjusting screw 35, the shank of which passes through the bottom of the housing with a knurled head at its outer end for manual turning. Adjustment of the screw 35 shifts the pivoted end of the arm 30, thereby adjusting the roller 31 with respect to the cam 29.

A member 36 in the form of an outwardly extending rib is secured at the outer side of the hub of the member 27. To cooperate therewith, a trip dog of bell crank lever form, having two arms 37 and 37a at right angles to each other, is pivotally mounted at the junction of the arms on bracket or arm 10. A pin 38 extends downwardly from the horizontal arm 37 and is in the path of movement of the member 36, so that when said member comes to the pin 38, by camming action thereagainst it, the attached clutch member 27, is moved on the shaft 26 to disengage from the clutch 25.

A link 39 connects the arm 37 of the trip dog with a rod 40 which passes through the upper end 2 of the housing. Its upper end is connected with the armature 41 of a solenoid 42. A guide sleeve 43 for the rod 40 is provided. Sealing gaskets or rings 44 to prevent the loss of oil from within the housing are used at the lower end of the member 19, around the shank of the adjusting screw 35 and around the rod 40 as shown.

At the lower end of the spindle or shaft 12 a

spinning tool, or a drill, reamer, countersink tool or other similar tools may be connected through suitable adapters therefor and in the usual manner that such tools are secured to shafts which drive them. In practice, for example in spinning, the work which is to be spun into shape, usually of sheet metal, may be placed in position below the spinning head when the shaft 12 is at its upper position, or conveyed thereto and stopped between the cycles of operation. The solenoid is energized momentarily and in suitable manner by closing a switch in an electric circuit in which the solenoid winding is included. The switch may be either automatically, manually or foot operated. On closing the switch, the armature 41 is elevated, thereby lifting the pin 38 which, under such conditions will be bearing against the member 36 and holding the clutch member 27 disengaged from its co-operating member 25. On lifting the pin 38 the two clutch members connect together, cam 29 being turned when such connection occurs. As shown in Fig. 1, the turning of the cam in a counterclockwise direction depresses the free end of the lever 30 which, bearing against the plate 18, forces shaft 12 downwardly with a compression of the spring 20. Such downward forcing of the shaft carries the spinning tool to the work which is to be processed. For spinning, the downward movement of the shaft 12 and the spinning tool connected therewith is uniform and continuous until the shoulder shown in Fig. 1 of the cam is reached, whereupon the spring 20 lifts the shaft 12 and the spinning tool connected therewith above the work.

When the shaft 26 has made one complete revolution the pin 38 will again be in position to be engaged by the member 36 to thereby disconnect the clutch 27. To insure that the pin 28 will be in such position, the arm 37a of the trip dog is provided. It, when the pin 38 is lifted, is moved into the path of movement of the member 36 which, on the rotation of clutch member 27, comes to the inner side of the arm 27a and moves it to return the pin 38 to the position where it will be engaged by the member 36 upon reaching such pin, thereby insuring that one revolution and one only of cam 29 shall take place. Such insurance provided by the structure described is more necessary when the head of the present invention is located horizontally than when it is located vertically. The energizing of the solenoid is momentary only, the circuit which supplies it with the necessary electric current being immediately broken upon release of pressure in the switch which closes the circuit.

As shown in Fig. 4 the bearing edges of the cam 29 are made up of a series of successive flattened steps 29a and 29b those at 29b being shorter than at 29a. They are so designed that the work shaft 12 may be properly advanced when it is desired that the spinning or drilling not be uniform and continuous, but in a series of successive steps. In a spinning operation, these steps make it possible to spin harder metal and at the same time obtain a smooth, properly formed spun surface. In drilling, these steps act as chip breakers. The drill enters the metal, being fed for a short distance, and then rotates for a short interval before the next successive time of feeding into the metal.

The cams which control the processing tools therefor are subject to variations in their peripheral edges which bear against the roller 31 in accordance with the type of operation which

is to be performed. It is to be understood that in practice the same head will not be used for drilling and spinning, for example, which would require a change in the cam 29. Each head does its own work and the cam in the head is designed for the particular operation which is to be performed.

In Fig. 8, the collar 16 is shown as a slip collar on the shaft 12, in order that it may disconnect from the shaft and be pushed downwardly thereon by the pressure of the lever 30 under those conditions when the pressure otherwise would be too great and more than what is required. Slipping of the collar on the shaft on the spindle 12 is designed to occur substantially at a predetermined pressure exceeding which might result in breaking or other damage to drills, reamers or the like. The spindle 12 where it is normally surrounded by the collar 16 is provided with a continuous annular groove 12a for the reception of balls 45. The collar 16 is formed with a plurality of radial passages 16a extending from its outer edge inwardly to the spindle, through which the balls are passed to the groove in the spindle, the balls normally being held in the groove by strong compression springs 46 housed within the passages 16a, the springs being compressed as shown by adjustable set screws by means of which the pressure of the springs against the balls may be adjusted. There may be a variable number of the radial passages 16a, in accordance with the design of the head for the work which it is to do.

When the pressure of a drill or other tool upon the work is substantially at the limits of safe pressure, with the springs 46 adjusted so that they will yield upon exceeding such pressure, increase beyond safe pressure compresses the springs and the balls which are ridden out of the groove 12a, the collar moving downwardly on the spindle which will be held, by reason of the upward pressure against it through the tool engaging the work, from further longitudinal downward movement. The collar will move along the spindle in a downward direction further compressing the spring 20, and will be returned by said spring 20 to its normal position shown in Fig. 8, when the pressure of the tool against the work is relieved. Such relief of pressure occurs when the cam actuated arm or lever 30 has completed its down stroke and starts to return to its upper position. The balls will return to the groove 12a and not go above such groove, as the strength of the spring 20 is not sufficient to disengage them from the groove by an upward pressure on the collar 16.

In spinning or countersinking or any similar processing, one valuable feature and result of our invention is that the spinning or countersinking tool may be adjusted inwardly or outwardly by turning the adjusting screw 35 while the head is in operation. The connected shafts 3 and 6 and also the tool carrying spindle or shaft 12 rotate continuously at high speed. The adjustment to control the extent of downward or outward movement of the spinning or other similar tool carried at the outer end of the shaft 12, while the shaft 12 is continuously driven, permits accuracy in a minimum of time, of the positioning of the spinning or other tool with respect to the work processed by it.

The structure described is very practical and useful and in its everyday continuous performance as now used it has proven especially satisfactory. Rapidity of production is attained together with uniformity in product.

The invention is defined in the appended claims

6
which are to be considered comprehensive of all forms of structure coming within their scope.

I claim:

1. In a structure as described a hollow housing, a driving shaft extending through one end thereof, a worm on the driving shaft, a second shaft in alignment with the driving shaft extending outwardly at the opposite end of the housing, connections between the adjacent ends of the shafts whereby the second shaft may be driven by and moved longitudinally with respect to said driving shaft, spring means normally moving the second shaft inwardly, a third shaft mounted in said housing at right angles to the driving and second shafts, a worm gear thereon meshing with said worm, a second gear on said third shaft, a fourth shaft rotatably mounted within the housing transversely thereof spaced from the third shaft, a gear thereon having a clutch member at one face loosely mounted on the fourth shaft and in meshing engagement with the second gear on the third shaft, a spring loaded clutch member slidably splined on the fourth shaft normally movable toward the first clutch member, a cam on said fourth shaft, a lever pivotally mounted at one end extending to one side of said cam and having a free end operatively associated with said second shaft, movement of the lever in one direction moving the second shaft outwardly against its associated spring means, a roller on said lever between its ends bearing against the cam, trip means for holding the second clutch member away from the first clutch member, means for releasing said trip means, and means on the second clutch member operatively engaging said trip means on one complete rotation of said fourth shaft for disconnecting the clutch members.

2. A structure as defined in claim 1, a slidably mounted member to which said lever is pivotally connected at one end located within the housing, holding and guiding means for said slidably mounted member, and a screw threaded into said slidably mounted member extending outwardly through a side of the housing, said screw being operable to adjust said slidably mounted member and the end of the lever connected therewith to control the position of the roller with reference to the cam.

3. A structure as defined in claim 1, said trip means comprising a pivotally mounted bell crank lever, a pin on one arm of said bell crank lever extending toward the second clutch member, a projecting member extending from the clutch member movable to and engaging said pin and having a cam slidably engaging the pin to withdraw the second clutch member from engagement with the first member, the other arm of said bell crank lever extending at right angles from the first arm and engaged by said projecting member to move the first arm of the bell crank lever to position the pin thereon in the path of movement of said projecting member on the second clutch member.

4. A structure as defined in claim 3, a link connected to the outer end of the first arm of the bell crank lever, a rod connected with the other end of said link, means through which the rod passes and in which it is slidably guided to outside the housing, an armature connected to the outer end of the rod, and a solenoid in which said armature is located.

5. In a structure as described, a hollow housing, a shaft having an inner portion within the housing, at its outer end extending beyond the housing, and at said end adapted to have a processing tool connected therewith, a driving shaft, con-

nections between said first and driving shafts for driving said first shaft by the driving shaft and for permitting longitudinal movement of the first shaft with respect to the driving shaft, spring means normally moving said first shaft inwardly, a lever having a free end operatively connected with said first shaft, said lever being pivotally mounted at its opposite end, a roller on the lever between its ends, a member to which said lever is pivotally connected movably mounted within said housing, a screw operable from outside the housing connected with said member for adjustment to vary the position of the pivoted end of the lever and the position of the roller carried by said lever, a third shaft, a cam on the third shaft engaging said roller, driving means between the driving shaft and the third shaft including a separable clutch for driving said third shaft when the clutch is connected, trip means movably mounted adjacent said clutch means on the separable clutch for disconnecting the clutch when the shaft and cam thereon have made a complete revolution, said trip means holding the separable clutch disconnected, and means for moving said trip means to release the clutch.

6. In a structure of the character described, a drive shaft, a work shaft axially aligned therewith, said work shaft being driven by said drive shaft and longitudinally movable with respect thereto, means urging said work shaft to retract toward said drive shaft, a pivotally mounted lever for urging said work shaft to advance away from said drive shaft toward an operating position, a cam for actuating said lever, means including clutch means for drivingly connecting said drive shaft and said cam, clutch control means for

automatically disconnecting said cam from said drive shaft upon completion of each cycle of rotation of said cam, and means for adjusting the position of the pivotal axis of said lever longitudinally with respect to said shafts.

7. In a structure of the character described, a drive shaft, a work shaft axially aligned therewith, said work shaft being driven by said drive shaft and longitudinally movable with respect thereto, means urging said work shaft to retract toward said drive shaft, a pivotally mounted lever for urging said work shaft to advance away from said drive shaft toward an operating position, a cam for actuating said lever, means including clutch means for drivingly connecting said drive shaft and said cam, clutch control means for automatically disconnecting said cam from said drive shaft upon completion of each cycle of rotation of said cam, and means for adjusting the position of the pivotal axis of said lever longitudinally with respect to said shafts, said cam having a predetermined irregular cam surface whereby said lever is actuated to advance said work shaft in accordance with a predetermined schedule during each cycle of operation of said cam.

ARTHUR NYQUIST.
